United States Patent

Des. 235,373
Patented June 10, 1975

235,373

DIGITAL CLOCK RADIO

Minol Araki, Tokyo, Japan, assignor to
Lloyd's Electronics Inc., Compton, Calif.

Filed Sept. 21, 1973, Ser. No. 399,283

Term of patent 14 years

Int. Cl. D14—03

U.S. Cl. D56—4 B

FIG. 1

FIG. 2

FIG. 3

FIG. 4

FIG. 5

FIG. 1 is a front elevational view of a digital clock radio showing my new design;

FIG. 2 is a rear elevational view;

FIG. 3 is a top plan view;

FIG. 4 is a bottom plan view; and

FIG. 5 is a right side elevational view, the left side being substantially identical thereto.

I claim:

The ornamental design for a digital clock radio, substantially as shown and described.
